D. L. MANSON

GOLF TEE

Filed Jan. 27, 1926

Fig. 3.

Donald L. Manson ^{Inventor}
By his Attorney
George C. Heinrich

UNITED STATES PATENT OFFICE.

DONALD L. MANSON, OF NEW YORK, N. Y.

GOLF TEE.

Application filed January 27, 1926. Serial No. 84,116.

This invention relates to improvements in golf tees, and more particularly in tees which are foldable so as to be conveniently transportable, and it is the principal object of 5 the invention to provide a golf tee adapted to be folded into a comparatively small compass adapted to be conveniently carried and set up without delay.

Another object of the invention is the provision of a golf tee made of duralumin or any other suitable metal which is light and durable, and well adapted to hold the ball in the exact position desired on the ground.

A further object of the invention is the provision of a golf tee of simple and therefore inexpensive construction well adapted to form an efficient pedestal for mounting the ball thereon preparatory to making a stroke, and which can be folded so as to protect 20 the tee when not in use.

These and other objects and advantages of the invention will become more fully known as the description thereof proceeds, and will then be more specifically defined in 25 the appended claims.

In the accompanying drawing, forming a material part of this disclosure:

Fig. 1 is a plan view of a golf tee constructed according to my invention.

Fig. 2 is a side elevation thereof, partly in section.

Fig. 3 is a side elevation thereof, folded.

As illustrated on the drawing, the golf-tee constructed according to my invention 35 comprises a disk 10 made of duralumin or any other suitable material which has attached thereto or made integrally therewith the tee 11 presenting a seat for a golf ball 12 indicated in broken lines.

A cross-piece or bar of duralumin or similar, suitable material is made in two parts 13 and 14, hinged together as at 15, so as to allow a folding upon one another.

The part 14 has attached thereto or made 45 integrally therewith a disc 16 made of lead or any other suitable material and provided with a centrally located opening 17 allowing the tee 11 to project therethrough when the device is folded to assume the position illustrated in Figure 3.

The operation of my novel tee device will be entirely clear from the above detailed description thereof, and it is to be understood that I have described and shown the preferred form of my device as an example of 55 the many possible ways to construct my device in practice and that such changes may be made in the general construction and the minor details thereof as come within the scope of the appended claims without departure from the spirit of the invention and 60 the principle involved.

Having thus described my invention, what I claim as new and desire to secure by Letters Patent is:

1. Golf tee comprising a metal disk, a tee integrally made therewith, a folding arm attached to said disk at one end, a guard for said tee attached to the opposite end of said arm, and provided with a central 70 perforation allowing the passage of said tee when the device is folded.

2. Golf tee comprising a disk of duralumin, a tee mounted thereon, a bi-partite arm, 75 hinges connecting the two parts of said arm, said disk attached to one end of one part of said arm, a lead disk attached to the opposite end of the other of said arms, said lead disk having a central perforation allowing the passage of said tee when the device is 80 folded for transportation.

3. Golf tee comprising a disk, a tee made integrally therewith and presenting a seat for a golf ball, a bi-partite arm, hinges connecting both parts of said arm at their inner 85 meeting ends, said disk made integrally with the end of one part of said arm oppositely disposed to said hinge, a lead disk made integrally with the outer end of the other part of said arm adapted to be folded upon the 90 same about said hinge, said lead disk having a centrally located opening allowing the passage of said tee when the device is folded into a comparatively small compass.

Signed at New York, in the county of New 95 York and State of New York this 21st day of January A. D. 1926.

DONALD L. MANSON.
